UNITED STATES PATENT OFFICE.

JAMES B. ANDERSON, OF SHALER TOWNSHIP, ALLEGHENY COUNTY, PENNSYLVANIA.

GAS BURNER.

Application filed August 18, 1923. Serial No. 658,026.

To all whom it may concern:

Be it known that I, JAMES B. ANDERSON, residing at Shaler Township, in the county of Allegheny and State of Pennsylvania, a citizen of the United States, have invented or discovered certain new and useful Improvements in Gas Burners, of which improvements the following is a specification.

My invention relates to improvements in gas burners, and particularly to the construction of the tips of the burners of blow torches, such as are used for cutting steel and other metals. The tip of a blow-torch burner embodying my invention is illustrated in the accompanying drawings.

Figure I is a view of the burner tip in side elevation, Figures II and III are views in longitudinal section; Figures IV and V are views in transverse section; and Figure VI is a view in end elevation. In Figure II the central body is shown in elevation, whereas in Fig. III both the outer body or shell and the central body are shown in section. The plane of section of Figs. II and III is indicated at II-II, Fig. VI. The planes of section of Figs. IV and V are indicated at IV-IV and V-V, Figure III. Figure VI shows the burner as seen from the right Figures I, II, and III.

The burner consists essentially of a central body 1, and a surrounding body 2. These bodies are of essentially cylindrical form and they telescope one within another, as the drawings clearly show. A key 3 may be provided so uniting them that as a unit they may be screwed to place. Both bodies are tapered to one end, the right-hand end, as shown in Figs. I, II, and III. The inner body 1 is provided with two sets of longitudinally extending grooves. One set of grooves 4 extends through the truly cylindrical portion of the body 1 and somewhat farther and into the tapered portion, and the other set of grooves 5 extends along the tapered portion of the body 1 from the extreme end thereof. It will be observed on comparing Figures IV and VI that there is no necessary correspondence in number between the two sets of grooves. In the instance here shown there are five of grooves 4, and one of them is obstructed by the key 3, whereas there are six of the grooves 5. It is, however, necessary that there be intercommunication between the grooves of the two sets. As here shown, both sets of

grooves meet in and merge in an open space 6, and there communication is effected. The open space 6 is formed by diminishing the diameter of the entire body 1 to approximately the diameter at the bottoms of the grooves, thus eliminating the grooves in that portion of the body structure. It should further be remarked of the structure of the inner body 1 that the truly cylindrical portion of it which is surrounded and enveloped in the truly cylindrical portion of the sleeve body 2, is greater in diameter than the adjacent portion to the left, and that the grooves 4 which are sunk in this part of the body portion 1 are sunk to such depth as to be flush with the cylindrical surface of the left-hand portion of this body member. Thus the gas has continuous passage from the space on the left, through the grooves 4, to the space 6 within the burner structure, and thence through the grooves 5 to the exit end, the right-hand end as shown in the drawings.

The body portion 1 is axially perforated from end to end with perforation 7.

In service it is the passageways formed by and between the grooves and the enveloping body which are the passageways for the gaseous fuel, and it is the axial passageway 7 which is the passageway for the blast of oxygen. The blast of oxygen affords the blow-torch function. The gaseous fuel advancing through the passageways formed by the grooves 4 and 5 is already mixed with air in sufficient quantities, that on emergence at the right-hand end of the burner tip, a light being there applied, the mixture burns in the air in a rosette of hot flames. When, the said rosette of flames being already lit, oxygen under high pressure is allowed to traverse the axial bore 7 combustion is intensified and a cone of flame of intense heating power and of oxidizing nature is powerfully projected from the burner tip.

The structure as thus far explained is known to the art. My invention concerns particularly the grooves 5 formed in the right-hand end of the body portion 1 of the burner, and in the shape of the passageways which are constituted by and between these grooves and the adjacent portions of the enveloping body 2. These passageways as hitherto formed are symmetrically arranged about an axis and are convergent axially. As hitherto formed, the grooves have been

round-bottomed, and of uniform section from end to end.

My invention is found first in causing these grooves 5 to increase in depth as the point of exit is approached, and so to form flaring passageways. Furthermore, the flare is inward, the passageways widen axially. Associated with this modification, I form the grooves rectangular in cross-section, rather than round-bottomed. This rectangular shape is shown in Fig. VI, while the flaring is best shown in Fig. III.

My burner, so improved in structure, I have developed particularly in the burning of butane gas, and with the end in view of obtaining with butane a flame well suited to such needs as the cutting of steel. Butane is a gas from which under combustion large heat values may be derived, but the problem has been to release them effectively. By forming the passageways of the burner tip of rectangular cross-section, and by deepening the grooves gradually to the exit and so forming flaring passageways, and, specifically, axially flaring passageways, I find that I can get unprecedented results.

The procedure in the use of these torches is, first, to allow the fuel gas in proper mixture to flow through the tip and to burn with a flame under which the work is initially heated. When such initial heating has been accomplished the blast of oxygen is turned on and the blow-torch effect is brought about. A long and intensely hot conical flame of oxidizing character is then powerfully projected from the burner. And under it the desired cutting is performed. I find that with a burner tip of the particular form described, the diminished rate of flow at the tip consequent upon the gradual enlargement of the passageways, and the concentration of the flow axially, increase very notably the heating effect of the torch during the initial step described, and that, during the ensuing cutting step, the blast of oxygen entrains and consumes the fuel gas with highly intensified effect.

I do not limit myself either to particular dimensions or to particular proportions. The drawings show a burner of my invention drawn to a scale somewhat larger than life-size. For illustration merely I give the actual dimensions of the grooves and passageways in a burner-torch tip which I have

made and have successfully used. The six grooves which in the accompanying drawings bear the reference numeral 5 are one thirty-second of an inch wide. They increase in depth from one thirty-second to one-sixteenth of an inch. The axial bore 7 for the oxygen blast is three sixty-fourths of an inch in diameter. With a burner tip having passageways of these dimensions and using butane, under a pressure of two pounds, I obtain a heating flame three-eighths of an inch long and of great heating effect, and then, when I apply oxygen under a pressure of thirty pounds, I obtain a blow-pipe flame of intense cutting power three inches long.

I am not in the practice of my invention limited to the use of butane. I mention butane because it is a gas of high heating value upon which I have worked, to make it effective for the end in view. Other gases, and particularly other hydrocarbon gases may be used to advantage in my improved blow torch.

I claim as my invention:

1. In a blow-torch burner structure a burner body provided with an oxygen passageway and with a plurality of gas passageways concentrically arranged about the axis of the said oxygen passageway and converging toward their exit, said gas passageways individually flaring to their exit.

2. In a blow-torch burner structure a burner body provided with an oxygen passageway and with a plurality of gas passageways concentrically arranged about the axis of the said oxygen passageway and converging toward their exit, the said gas passageways individually flaring toward the axis as they approach their exit.

3. In a blow-torch burner structure a burner body provided with an oxygen passageway and with a plurality of gas passageways symmetrically arranged about the axis of the said oxygen passageway, said gas passageways individually being of rectangular cross-section and flaring to their exit.

In testimony whereof I have hereunto set my hand.

JAMES B. ANDERSON.
